UNITED STATES PATENT OFFICE.

JOSHUA K. CLUTTS, OF DETROIT, MICHIGAN.

CHARGING DEVICE FOR BLAST FURNACES.

Application filed September 25, 1922. Serial No. 590,496.

To all whom it may concern:

Be it known that I, JOSHUA K. CLUTTS, a citizen of the United States of America, residing at Detroit, in the county of Wayne 5 and State of Michigan, have invented certain new and useful Improvements in Charging Devices for Blast Furnaces, of which the following is a specification, reference being had therein to the accompanying drawings.

This invention relates to charging devices for blast furnaces.

It is the object of the invention to provide for delivery to a blast furnace of 15 charges of hot ores which have been subjected to a preliminary reduction in a rotary kiln and to weigh each charge accurately as it is delivered.

A further object of the invention is to 20 provide power actuated means for delivering a known weight of ore from a rotary kiln to a blast furnace and to automatically control in unison with said means a top closure for the blast furnace and a closure 25 for the inlet to the weighing receptacle.

In the drawings:—

Figure 1 is a view in side elevation of the 30 improved charging means sectionally showing the upper portion of a blast furnace;

Figure 2 is a plan view of the same;

Figures 3 and 4 are sectional details of a loose connection between the charging device and its actuating means;

Figure 5 is a vertical cross section view 35 of the charging box, showing the closure for the chute which delivers ore to said box in its position cutting off the flow of ore.

In said views the reference character A designates a blast furnace provided with a 40 sliding cover B which, to reduce the friction incident to its closing and opening movements is preferably mounted upon wheels C traveling upon a track D. E is a rotary kiln which subjects the ore delivered to said furnace to a preliminary reduction process. Said kiln is mounted at a gradual 45 inclination, its lower extremity extending adjacent the top of the furnace and a non-rotative section E' being provided at said extremity. Engagement between the rotating and stationary portions of the kiln is maintained in any suitable manner, as for example by forming one of said portions with an annular flange G which is engaged 50 by a return-bent flange F upon the other portion. H is a charging box, preferably

rectangular, to which box a discharge chute I is downwardly extended from the stationary kiln member. Said box is mounted upon the platform J of a weighing scale, 60 the beam of which is indicated at K. Into said box there is axially extended the front portion L of a plunger rod L, L', the rear portion L' of which enters an air cylinder M and is attached to a piston N reciprocating in said cylinder. Reciprocation of said plunger and rod is adapted to be effected by an alternate introduction of air into the respective extremities of said cylinder through pipes O controlled by valves P. 70 The front portion L of said rod carries two plunger heads R and R' adapted to snugly enter the box H, said heads being so spaced as to close the respective ends of the box in the retracted position of the rod L, L', 75 shown in full lines in Figure 1. In said position the kiln is permitted to discharge through the chute I into said box between said plunger heads, as Figure 1 clearly shows. The forward plunger rod R is so 80 connected to the closure B of the blast furnace that the two will move in unison when power is applied. Thus when the plunger is projected, the heads R and R' and the closure B occupy the position shown in dash 85 line in Figure 1, the closure being shifted clear of the furnace during the projecting movement and the two plunger heads being moved into proximity with opposite sides of the furnace mouth so that the charge of 90 ore which is discharged from the box H during the projecting movement is delivered into the mouth of the furnace. To prevent entrance of ore to the charging box rearward of the plunger head R', there is secured to 95 the latter a closure member S which is brought beneath the chute I as the plunger heads travel forwardly, preventing any downflow of ore until said plunger head has been retracted beyond the outlet of said 100 chute. S' indicates a reinforcing bracket attaching the closure S to the rod L, L'.

To permit the scale platform J to register the weight of the box H and its contents without error due to the actuating connection established through the plunger rod L, L' to the air motor M it is preferred to employ a loose connection between the parts L and L' of said rod. Thus, as is best seen 105 in Figures 3 and 4, heads U' and U are mounted upon the rod members L and L' respectively and interlock as shown in Fig- 110

ure 3 when the rod is under thrust. When the rod is under a tension strain, however, as is the case where the plungers R and R' are being retracted the heads U' and U are drawn apart as shown in Figure 4, the casting U² then transmitting the pull from the portion L' of the rod L, L' to the portion L thereof. This relative position of said heads is maintained during charging and weighing of the box H so that the section L may undergo the necessary slight vertical movement with respect to the section L' occurring during weighing. A pin and slot connection W from the forward plunger head R to and an arm W' upon the cover B also permits the necessary slight vertical movement of the charging box with respect to said cover.

The described device by delivering known weights of ore to the furnace permits accurate control of proportion and secures a high grade of iron.

The discharge chute I may be provided with a lateral outlet W² normally closed, as indicated at W³, said outlet being uncovered in case for any reason it is necessary to discontinue charging the furnace temporarily.

What I claim as my invention is:—

1. In a charging device, the combination with a blast furnace, of a closure therefor, a container for a quantity of ore, means for weighing said container and its contents, and a common means for shifting said closure to open position and for delivering the contents of said container into the blast furnace.

2. In a charging device, the combination with a blast furnace having an inlet at its top, of a charging box adjacent said inlet, means for weighing said box and its contents, a pair of connected plungers occupying the respective ends of said box in a retracted position, and means for projecting said plungers for substantially registering the same with the furnace inlet.

3. In a charging device, the combination with a blast furnace, of a sliding closure therefor, a charging box adjacent said closure, and a plunger operable in said charging box and connected to said closure whereby ejection of the contents of the charging box into the blast furnace and opening of said closure is accomplished in one operation.

4. In a charging device, the combination

with a blast furnace, of a charging box adjacent the same, a closure for said furnace, a plunger operating within said box, a weighing platform carrying said box, and loose connections between said plunger and closure and the actuating rod whereby weighing of the box and its contents is accomplished independently of the closure and rod.

5. In a charging device, the combination with a charging box, of a chute rising from said box for discharging material thereinto, a member reciprocatory in said box for discharging measured quantities of material therefrom, said chute having a lateral opening providing for the discharge of material when the box is temporarily out of use, and a closure adjustable to control said opening.

6. In a charging device, the combination with a charging box having its top provided with an inlet for material, a member reciprocatory in said box for discharging measured quantities of the material, a weighing platform carrying said box, actuating means for said plunger, and a connection between said means and plunger providing for vertical movement of the latter relative to the former incident to functioning of the weighing platform.

7. In a charging device, the combination with a blast furnace having its top provided with a sliding closure, of a charging box for said furnace, said box having an inlet thereto for the charging material, a member reciprocatory in said box for effecting a measured discharge of material therefrom into said furnace, an actuating means for said reciprocatory member mounted independently of the weighing platform, an actuating connection between said means and reciprocatory member providing for a relative vertical movement of the latter relative to the former incident to the operation of said weighing platform, and a connection between said reciprocatory member and the closure of the furnace for reciprocating the latter in unison with the former, said connection providing for a limited vertical movement of said member relative to the closure incident to operation of the weighing platform.

In testimony whereof I affix my signature.

JOSHUA K. CLUTTS.
